UNITED STATES PATENT OFFICE

ARTHUR THOMAS AND GEORGE CRAIG, OF THORNTON HEATH, ENGLAND, ASSIGNEES
TO THE ACCOUNTING & TABULATING CORPORATION OF GREAT BRITAIN LIMITED,
OF LONDON, ENGLAND

MACHINE FOR PERFORATING STATISTICAL CARDS

Application filed February 17, 1931, Serial No. 516,301, and in Great Britain February 28, 1930.

This invention relates to machines for perforating statistical cards, and has for its object to simplify the keyboard of a perforating machine for punching statistical record cards, and further to simplify the mechanism of such machines so that power is coupled to the operatives of the punching mechanism as a result of operating the keyboard of the typewriting machine, and still another object is to simplify the keyboard of a perforating machine so that for manual operation a much lighter touch is required than has heretofore been obtained.

In accordance with the present invention the load is taken off the keyboard by introducing a relay, as for instance a continuously rotated roller for actuating the operatives for setting the set bars of the machine.

In perforating machines of the kind wherein the set bars are displaced by plungers actuated through bell cranks, in turn moved by the agency of Bowden mechanism actuated from the keyboard, the set bars according to the invention are moved by power actuated on the manual selection made by operating the keys.

Preferably the power operated and continuously rotating roller is disposed between the Bowden mechanism and the keyboard, the keyboard being merely employed to selectively connect to the rollers operative members corresponding to the keys, which when operated by the roller actuate the Bowden mechanism corresponding to the respective set bars.

The introduction of power to what is normally a hand operated machine introduces the difficulty that the operator may dwell on the keys and the power actuated roller will cause a rapid sequence of the same operations in the machine, resulting from the set bar connected parts being maintained in operative relation with the motive member, namely the roller.

According to the present invention a machine with power actuated operatives brought into operation by connecting the operatives to the motive member, as for example, the roller, as a result of operating the keys, comprises means for preventing repetition action,

in other words the means assure one action only for the depression of a key however long it is held down.

In order that the invention may be more clearly understood, reference will now be made to its application to a perforating machine of the kind described in the specification of Thomas United States Patent No. 1,858,174 which, according to the invention may be modified in order to take the load off the keyboard by associating with the bell crank operatives, a relay, as for example a continuously rotated roller, so that the operating rods of the translating device merely rock levers into engagement with the continuously rotated roller so that power is employed to actuate the bell cranks and to set the set bars.

The perforating machine so modified conveniently includes connections from the bell cranks of the set bars brought forward into alignment.

The invention may be carried out in various ways, but a preferred construction according thereto is illustrated by way of example in the accompanying drawings, in which the invention is shown as applied to a perforating machine as described in the specification of Thomas, United States Patent No. 1,858,174.

In the drawings

Fig. 1 shows the keyboard in sectional elevation.

Fig. 2 is an end view.

Fig. 3 is a plan view with the keys removed, and

Fig. 4 shows an alternative form of a detail of the mechanism.

In the construction illustrated in the drawings, each key 1 in each row of the four rows comprised in the bank of keys is provided with a bell crank 2. Conveniently, the bell cranks of each key of a row are co-axially pivoted as at 3. Each bell crank 2 on the depression of its respective key 1 engages a pin 4 on a longitudinally displaceable key bar 5 which rests on a pivoted control lever 6 by a lug 7 on the underside of the key bar 5. Displacement of the key bar by operation of a key brings the lug 7 over a notch or gap 8

on the control lever 6. This permits the control lever to rise to the depth of the lug under the action of a spring 19 hereinafter referred to.

On each control lever 6 is eccentrically mounted a toothed wheel 10. The eccentric toothed wheels 10 of all the control levers 6 are in co-axial alignment and the displacement of the control lever permitted by the lug 7 on the key bar 5 in the gap 8 of the control lever brings the eccentric toothed wheel 10 into engagement with a continuously driven roller 11 having ratchet teeth. The engagement of the roller 11 with the eccentric 10 turns the eccentric and according to the throw of the eccentric the control lever is displaced angularly which displacement is utilized to actuate a plunger 12, the movement of which is transmitted conveniently by a Bowden cable 13 to the bell cranks of the perforating machine actuating a plunger on the set bar.

In such an arrangement, therefore, the depression of the key introduces a relay between the Bowden mechanism and the key whereby the set bars are power actuated on the manual selection made by operating the keys.

Each key bar 5 is conveniently spring controlled for resetting immediately a key is released, and to prevent a continual operation of the respective control lever as a result of holding down a key or otherwise maintaining a key bar displaced, the control lever is provided with a pivoted latch member 14 mounted at the end of the control lever remote from its pivot.

Adjacent the latch is disposed a pivoted shutter 15 connected by a link 16 to a second pivoted shutter 17 adapted to be turned about its pivot 18 by movement of the key bar 5. When the key 1 is depressed and the lug 7 on the key bar is brought into register with the gap 8 in the control lever 6, the latter rises as before, but when it reaches the bottom of its stroke, a spring 19 attached to the latch 14 pushes the latch into such a position that it engages with the bottom of the adjacent pivoted shutter 15 which has been pushed into a position which renders its engagement possible by the movement imparted to it by the key bar through the other pivoted shutter 17 and the connecting link 16; thus as long as the key is held depressed the pivoted shutter 15 is held in such a position as to engage the latch 14 on the control lever, whereby the return of the latter to its normal position is prevented. As soon as the key is released the shutters 15, 17 spring back under the action of springs attached thereto, thereby freeing the latch 14 and permitting the control lever 6 to rise. When the key is released the key bar 5 is returned by means of a spring 5a.

Alternatively, the control lever may be

provided with a stirrup latch 114 adjacent the gap (see Fig. 4), the latch being spring controlled so that as the control lever is displaced by its eccentric being turned by the roller, the latch jumps over the gap and acts as a bridge preventing re-engagement of the lug on the respective key bar with the gap, as a result of the control lever rocking. Displacement of a key bar causes its lug to rock the stirrup 114 out of the way before entering the gap on the control lever.

A relay operated perforating machine for statistical cards as above described can be very simply connected up to a relay operated typewriter as described in the specification of Thomas co-pending United States patent application Serial No. 510,712 of which the title is "improvements in mechanism normally operated from a keyboard". To this end there may be juxtaposed to the end of each key bar 5 of the perforating machine an operating lever 20, the operating lever being rocked, conveniently by Bowden mechanism 21, from the corresponding operating rod of the typewriter thereby causing movement in the key bars of the perforating machine as if the key bar had been manually displaced as above described.

Although the invention has been described in relation to perforating machines as described in the specification of Thomas, United States Patent No. 1,858,174, this is by way of example only, as the invention comprises broadly the employment of power between the set bars of a perforating machine and the keys for setting the set bars, and also the employment of a relay mechanism between any keyboard and operatives such as punch mechanism where a plunger is operated as a result of being selected from the keyboard, for instance the invention covers the employment of relay mechanism between the keyboard and plungers of a verifying apparatus, and in such forms of apparatus means may be provided for indicating errors in the card being verified, either immediately the error is detected or by means of a sorting operation, in other words the invention covers the employment of relay power mechanism between a keyboard and displaceable pins or plungers such as are used in machines dealing with statistical cards.

In addition the invention covers the employment of relay mechanism between a carriage return key and carriage return mechanism, which may, for example, be as described in the Thomas and Blamey's specification of co-pending United States patent application Serial No. 516,302 of which the title is "improvements in keyboard operated machines" and also between a back spacing key and back spacing mechanism, such for example, as that described in the same co-pending United States patent application No. 516,302.

What we claim is:—

1. In a keyboard controlled machine the combination of a plurality of plungers adapted to produce holes in statistical cards, a key bar for each key, an operative connection between each key and its key bar, a downwardly depending lug on said key bar, a pivoted control member having a recess in its upper surface, means for urging said control member upwardly whereby the upper surface of the control member bears against the downwardly depending lug on the key bar, a toothed wheel mounted eccentrically on the control member, a second toothed wheel adapted to be rotated continuously, whereby when a key is depressed the key bar is displaced until the lug thereon registers with the recess in the control member thereby bringing the eccentric toothed wheel into engagement with the continuously rotating toothed wheel whereby the control member is depressed, and an operative connection between the control member and a plunger and means for restoring the key bar when said key is released.

2. In a keyboard controlled machine the combination of a plurality of plungers adapted to produce holes in statistical cards, a key bar for each key, an operative connection between each key and its key bar, a downwardly depending lug on said key bar, a pivoted control member having a recess in its upper surface, means for urging said control member upwardly whereby the upper surface of the control member bears against the downwardly depending lug on the key bar, a toothed wheel mounted eccentrically on the control member, a second toothed wheel adapted to be rotated continuously, whereby when a key is depressed the key bar is displaced until the lug thereon registers with the recess in the control member thereby bringing the eccentric toothed wheel into engagement with the continuously rotating toothed wheel whereby the control member is depressed, an operative connection between the control member and a plunger means for restoring the key bar when said key is released, a latch pivoted to the control member and means whereby said latch holds the control member in the lower position until said depressed key is released thereby preventing repetition action.

3. In a keyboard controlled machine the combination of a plurality of plunger adapted to produce holes in statistical cards, a key bar for each key, an operative connection between each key and its key bar, a downwardly depending lug on said key bar, a pivoted control member having a recess in its upper surface, means for urging said control member upwardly whereby the upper surface of the control member bears against the downwardly depending lug on the key bar, a toothed wheel mounted eccentrically on the control member, a second toothed wheel

adapted to be rotated continuously, whereby when a key is depressed the key bar is displaced until the lug thereon registers with the recess in the control member thereby bringing the eccentric toothed wheel into engagement with the continuously rotating toothed wheel whereby the control member is depressed, an operative connection between the control member and a plunger, a latch pivoted to the control member, a pivoted shutter, spring means for maintaining said latch against the side of said pivoted shutter, a second pivoted shutter bearing against the end of the key bar, an operative connection between said two pivoted shutters, whereby both shutters are rocked when the key bar is displaced and the latch moves under the edge of the adjacent pivoted shutter when the control member is at the bottom of its stroke to thereby hold the control member in such position until said depressed key is released, means for restoring the key bar when said key is released thereby freeing the shutters, and means for restoring the shutters whereby the latch is freed from the shutters.

4. In a keyboard controlled machine the combination of a plurality of plunger adapted to produce holes in statistical cards, a key bar for each key, an operative connection between each key and its key bar, a downwardly depending lug on said key bar, a pivoted control member having a recess in its upper surface, means for urging said control member upwardly whereby the upper surface of the control member bears against the downwardly depending lug on the key bar, a toothed wheel mounted eccentrically on the control member, a second toothed wheel adapted to be rotated continuously, whereby when a key is depressed the key bar is displaced until the lug thereon registers with the recess in the control member thereby bringing the eccentric toothed wheel into engagement with the continuously rotating toothed wheel whereby the control member is depressed, an operative connection between the control member and a plunger, and a stirrup latch pivoted to the control member adjacent the recess thereon, said latch being pushed to one side by the key bar when said key bar is displaced by depression of a key, spring means for moving said latch under the lug on the key bar when the control member is at the bottom of its stroke, whereby said control member is held in such position until said key is released, and means for restoring said key bar upon release of said key, whereby the latch is freed from the lug.

5. In a keyboard controlled machine, the combination of a plurality of plunger in said machine adapted to produce holes in statistical cards, a key bar for each key, an operative connection between each key and its key bar, a downwardly depending lug on said key bar, a pivoted control member having a

recess in its upper surface, means for urging said control member upwardly whereby the upper surface of the control member bears against the downwardly depending lug on the key bar, a toothed wheel mounted eccentrically on the control member, a second toothed wheel adapted to be rotated continuously, whereby when a key is depressed the key bar is displaced until the lug thereon registers with the recess in the control member thereby bringing the eccentric toothed wheel into engagement with the continuously rotating toothed wheel whereby the control member is depressed, an operative connection between said control member and a plunger in said machine, a pivoted operating lever juxtaposed to the end of said key bar whereby said key bar is displaced when said lever is rocked, means whereby said lever may be operatively connected to the keys of a second machine so as to be rocked when a key is depressed in said second machine, whereby the control member is depressed and means for restoring said key bar when a depressed key is released.

6. Power operated relay mechanism for a keyboard controlled machine, comprising a displaceable key bar, means for connecting said key bar to a key, whereby said bar may be displaced by depression of the key, a pivoted control member having a recess in its upper surface, a downwardly depending lug on said key bar normally abutting the upper surface of said control member and adapted to register with the said recess when the key bar is displaced, means urging said control member upwardly, a rotary member adapted to be continuously rotated, an eccentric member pivoted on said control member and adapted to engage with said rotary member when said lug registers with said recess, means for connecting a part of the machine controlled by said key to the control member, whereby said part is operated when said eccentric member engages said rotary member and means for returning the key bar when said key is released after depression.

7. Power operated relay mechanism according to claim 6, with latching means for ensuring that said part is operated once only for one depression of the key.

8. In testimony whereof we affix our signatures.

ARTHUR THOMAS.
GEORGE CRAIG.
